UNITED STATES PATENT OFFICE.

WILLIAM C. RENGERT, OF SOUTH BEND, INDIANA, ASSIGNOR TO THE STUDEBAKER CORPORATION, OF SOUTH BEND, INDIANA, A CORPORATION OF NEW JERSEY.

POURING-LADLE EQUALIZER.

Application filed April 27, 1925. Serial No. 26,126.

To all whom it may concern:

Be it known that I, WILLIAM C. RENGERT, a citizen of the United States of America, and resident of South Bend, in the county of St. Joseph and State of Indiana, have invented certain new and useful Improvements in Pouring-Ladle Equalizers, of which the following is a specification.

This invention relates to foundry apparatus and the like and particularly to apparatus used in connection with pouring ladles of a size too large to be handled by hand.

Such ladles must of necessity be handled by a crane or other mechanical carrier of such description, and as the ladle is moved from mold to mold, in the operation of pouring the same, it has been necessary for the operator of the crane, in the past, to raise the ladle by drawing up the crane hook in order to compensate for the relative lowering of the lip of the ladle in respect to the molds which occurs due to the increased amount that the ladle must be tipped to pour as the metal is poured from it into the molds. Inasmuch as the cranes used for this purpose are generally of the overhead traveling type in which the operator is usually at a considerable distance from the ladle, and is consequently unable to accurately judge the amount which the crane hook must be raised to bring the lip of the ladle into the required space but adjacent relation to the sprue-hole in the successive molds, considerable inconvenience and loss of time has been experienced, and for this reason it has sometimes been deemed advisable to resort to the smaller hand-carried ladles in preference thereto, with the resulting slowness of operation and increased labor charges.

Having the above in mind, it is the principal object of the present invention to provide means for automatically lifting the ladle as the metal is being poured therefrom an amount necessary to keep the pouring lip of the ladle at a constant distance from the upper surface of the mold, or series of molds of the same height, thus eliminating any necessity for controlling the height of the ladle in respect to the mold on the part of the crane operator.

Another object is to provide a device interposed between the crane hook and the ladle for automatically governing the position of the ladle in respect to the crane

hook in accordance with the amount of metal carried by the ladle.

A further object is to provide, in combination with a pouring ladle and a crane hook, a spring-controlled equalizing device in the connection between the two, whereby for each increment of drop in the height of the metal in the ladle, the ladle will be raised a proportionate increment, whereby the distance between the pouring level of the lip of the ladle will be at a substantially constant distance from the crane hook throughout the operation of pouring.

The above being among the objects of the present invention, the same consists of certain features of construction, combination of parts and method of application to be hereinafter described with reference to the accompanying drawings, and then claimed, having the above and other objects in view.

In the accompanying drawings which illustrate a suitable embodiment of the present invention, and in which like numerals refer to like parts throughout the several different views.

Figure 1 illustrates, more or less diagrammatically, the interior of a foundry, showing numerous molds positioned on the floor thereof ready to be filled with metal from a ladle carried by an overhead traveling crane, the application of an equalizer between the crane hook and ladle, as covered by the present invention, being shown.

Figures 2, 3 and 4 are more or less diagrammatic views of the crane hook, equalizer, ladle and mold, showing the relative relation that these parts assume in respect to each other in accordance with the amount of metal in the ladle during the operation of pouring a mold or series of molds.

Figure 5 is a side elevation of the equalizing device shown inserted between the crane hook and ladle in the previous views.

Figure 6 is a side elevation of the equalizing device of Figure 5 but turned ninety degrees around the axis thereof from the position shown in Figure 5.

Figure 7 is a sectional view taken on the line 7—7 of Figure 6.

Figure 8 is a partially broken sectional view taken on the line 8—8 of Figure 5.

Figure 9 is a sectional view taken on the line 9—9 of Figure 7.

In Figure 1 is indicated a portion of a foundry on the floor of which are arranged

numerous molds 15 which are ready to be poured or filled with metal. As is usually the case these molds are placed in double rows with an aisle between each double row so that it is possible to pass along each and every mold to pour the same, the sprue hole into which the metal is to be poured being positioned on the aisle side of the mold if possible. As is usual in large production foundries, there are a large number of molds of the same height, and all of the molds of the same height are placed in a separate group for ease of pouring as will hereinafter be apparent. Time and labor can usually be saved in the pouring of such molds if a relatively large ladle is used because there is less tendency for the metal to chill in a given length of time than with a small ladle and fewer laborers are required in the operation of pouring a given number of molds. In order to handle these large ladles it is necessary to provide some type of mechanical carrying means, and although such means may be of the single overhead track type, in which case a row of molds is placed along each side of the track, it is usually more expedient to use an overhead traveling type of crane, although any suitable means may be employed.

30 In Figure 1, for the purpose of illustration, is shown an overhead traveling crane which comprises a bridge 16, usually extending clear across the width of the foundry floor and supported above the same on two longitudinally extending parallel tracks 17 which in turn are supported from the floor by vertical columns 18. The bridge 16 is provided with wheels or trucks on either end which may be driven by a suitable electric motor (not shown) controlled by an operator in a cab 19 depending from one end of the bridge 16, so that the bridge may be run from end to end of the tracks 17 over the length of the floor. The bridge 16 is provided with tracks on its upper surface over its full length which carry a trolley 20, driven by an electric motor 21 and controlled from the cab 19, the trolley 20 being thereby capable of traveling from end to end of the bridge 16.

55 The trolley is provided with an electrical- ly controlled winding drum or hoist around which a cable 22 is wound and which extends down through the sheave 23, which carries the crane hook 24, and back to the trolley in a conventional manner, so that the hook may be raised or lowered thereby. From the above it will be evident that by moving the bridge up or down the length of the foundry and by moving the trolley across the length of the bridge the crane hook may be readily moved to any point in the crane way.

60 Heretofore it has been the practice to suspend the ladle, designated as 25 in the draw-

ings, from the hook 24 by an inflexible connection such as a chain, link or the like, which extends between the hook 24 and the bail 26 of the ladle which is pivoted thereto at 27. The crane is operated to bring the 70 ladle into close proximity with one of the molds 15 and in such position that when the ladle 25 is tipped about its pivot point 27 its pouring lip 28 will be in such a position that the molten metal in the ladle will be directed into the sprue hole 29 of the mold. In pouring such molds it is essential that the lip 28 be within a certain close proximity to the upper surface of the mold so that the metal flowing out of the ladle will not drop such a distance to the mold that its impact against the same will materially loosen any 80 of the particles of sand from which the molds are made and wash such particles into the part being cast. Thus, in pouring a row of 85 molds, the ladle 25 is brought into adjacent relationship with the end mold, the ladle is tipped by a handle such as 30 (Figure 1) or other suitable means, to a point where the metal in the ladle is about to flow from the 90 lip thereof, the crane operator operates the lifting mechanism of the crane to bring the lip into proper close relationship with the upper surface of the mold and the ladle is then further tipped to cause the metal therein to run into the mold. When the mold is 95 filled the ladle is tipped back sufficiently to prevent pouring of the metal from the ladle and the crane operator causes the trolley 20 to move along the bridge 16 until the 100 ladle 25 is in position to pour the next mold, and the operation of pouring is repeated.

105 It will be evident that as the ladle 25 travels from mold to mold in pouring the same, the level of the metal in the ladle will be continuously lowered, and as the level of the metal is lowered it will be necessary to tip the ladle more each time to allow the metal to run out of it, and that the more the ladle is tipped the closer the lip 28 will approach the upper surface of the mold. Inasmuch as it is desirable to keep the lip 28 in 110 as close proximity to the upper surface of the mold 15 as is practically possible in the operation of pouring, it will be evident that unless the ladle is raised at certain intervals, depending upon the size of the ladle and the amount of metal taken by each mold, the lip 28, through the tipping of the ladle 25, 115 will be dropped to such an extent that it will 120 strike the upper surface of the mold to the damage of the latter. For this reason it is necessary for the crane operator to control the mechanism to lift the ladle at certain intervals. Due to the fact that the crane operator is usually at some distance from the ladle, it is difficult for him to judge the exact amount which the ladle must be raised 125 in each case to keep the lip 28 in the required position, and usually he must depend upon 130

signals from others placed in such a position as to be capable of more readily determining this fact. The operation of the crane in accordance with directions from the floor is not, at the best conducive to the rapidity which is desirable in this work to avoid possible freezing of the metal in the ladle, and it is the necessity of such raising of the ladle at frequent intervals by the operator of the crane that the present invention contemplates eliminating.

This is accomplished by inserting in the suspension connection between the crane hook 24 and the bail 26 of the ladle 25 a device 31 which I prefer to call an equalizer. This device is such that for a given drop of the level of the metal in the ladle 25, the connection between the ladle 25 and crane hook 24 is automatically shortened a proportionate amount, so that as the metal is gradually poured out of the ladle 25 the latter is gradually and automatically raised so that the level of the metal therein, and consequently the lip 28 of the ladle when in pouring position, remains at a substantially constant distance from the upper surface of the molds without any necessity of raising the crane hook 24 on the part of the crane operator.

The construction of an equalizer 31 suitably constructed in accordance with the present invention is illustrated in Figures 5 to 9 inclusive. As shown it comprises a cylindrical shell, which for the sake of convenience is also designated as 31, provided with a cap 32 closing the lower end thereof. Within the shell 31 and normally positioned adjacent the upper end thereof is a circular block or slide 33 which loosely engages the interior of the shell 31 and is slidable longitudinally therein. Depending from the slide 33 and secured thereto at its free ends by the nuts 34 is a U shaped member or bail 35 which extends down through and projects out past the lower face of the cap 32 in which openings are formed to slidably receive it. Two cylindrical tubes 36 resting against the upper face of the cap 32 within the shell 31 extend upwardly therefrom and project through the slide 33 in which they are slidably received, and receive against their upper ends the inturned lower ends of the bail or handle 37. Rods 38, threaded on each end to receive nuts 39, extend up through each of the tubes 36 and through the inturned ends of the bail 37 above which they receive the nuts 39, and also extend beneath the cap 32 to receive the nuts 39 on the lower ends of the rods. The tubes 33 thereby act as spacers between the bail 37 and the cap 32 which are secured together in spaced relationship by the rods 38 and nuts 39. The slide 33 and bail 35 are normally held up in the position shown by means of two heavy coil springs 40 which

surround the tubes 36 and extend between the cap 32 and slide 33. These coil springs 40, by reason of the force necessary to compress them a given amount, control the longitudinal position of the slide 33 in respect to the shell 31 in accordance with the force acting to separate the bails 35 and 37.

In practice, as shown in Figures 1 to 4 inclusive, the bail 37 is slipped over the crane hook 24 and a link 41 provided with hooked ends connects the bail 35 with the bail 26 of the ladle 25. When the ladle is full of metal, it will be evident that the weight thereof, which is carried by the crane hook 24 through the medium of the equalizer 31, will cause a certain compression of the springs 40, thus causing the bail 35 to extend or project out from the lower face of the cap 32 an amount (designated as "a" in Figures 2, 3 and 4) proportionate to the weight of the metal in the ladle 25. As the weight of the metal in the ladle diminishes during the pouring operation, the springs 40 will expand an amount proportionate to the diminution of such weight and the distance "a" will be decreased, thereby diminishing the distance (designated as "b") between the ladle 25 and crane hook 24, and thereby raising the ladle 25. The springs 40 have such a deflection under a given load, or as it is commonly said, have such a "weight", that the increase in the length of the spring due to the decrease in the weight of the metal in the ladle, is substantially equal to the decrease in the level of the metal in the ladle, so that the actual level of the metal remains in the same relative position in respect to the top of the mold (designated as distance "c") whether the ladle be full or nearly empty. To illustrate, suppose the ladle is of such a diameter that the weight of a layer of metal in it one inch thick is one hundred pounds. To equalize this springs 40 are provided which have a deflection rate of fifty pounds to the inch or a combined total of 100 pounds to the inch for the two. In such a case if an inch thickness of metal is poured from the ladle, decreasing the level of the metal one inch, the springs will expand an inch and leave the relative position of the level of the metal in respect to the mold unchanged. This relative movement of the springs to the level of the metal takes place for each increment of metal poured from the ladle with the result that the distance "c" remains substantially constant throughout the pouring operation without a change in the distance (designated as "d") of the crane hook 24 from the floor. While, of course, due to the change of area of the surface of the metal in the ladle 25 as the ladle is tipped, it is impossible to compensate for the change of level of the metal exactly, yet it has been found that the variation in

the distance "c" is so slight as to be negligible and that once the distance "d" is set no further movement of the crane hook in such a direction is necessary. The crane operator is, by the use of such a device, freed of any necessity for controlling the height of the ladle 25 and the operation of pouring the molds 15 may progress without delay in this direction.

10 It will also be evident that inasmuch as the equalizer has a given rate of deflection, it must be used in conjunction with such a sized ladle and for such metal as will correspond thereto. If, for instance, a larger 15 diametered ladle is used, an equalizer having a smaller rate of deflection corresponding thereto must be used for the same metal, and if for instance, aluminum is to be 20 poured instead of cast iron, an equalizer having a greater rate of deflection must be used for a given size of ladle. Inasmuch as the level of the metal in the ladle 25 corresponds at all times to the height of the lip 28 of the ladle 25 when in pouring 25 position above the upper face of the molds 15, the height of the lip 28 above the molds 15 when once set, automatically remains substantially constant.

It will be apparent that the construction 30 of the equalizer may be varied to suit different needs or fancies as the case may be, and that any device which compensates for the drop of the level of the metal in the ladle by raising the latter may be substituted in place of the one shown and described with like results, and I do not limit myself to the specific construction shown and described but claim as my invention all that is as broadly novel as in commensurate with 35 the appended claims.

What I claim is:—

1. The combination with a crane and a ladle suspended therefrom, of means in the connection between said crane and said ladle whereby said ladle is automatically raised when the level of the contents of said ladle is lowered.

2. The combination with a crane and a liquid carrying ladle suspended therefrom, 50 of means in the connection between said crane and said ladle whereby when the level of said liquid is lowered in said ladle said connection will be automatically shortened, thereby raising said ladle.

3. In combination, a crane hook and a liquid carrying ladle, means for suspending said ladle from said hook, and an automatically actuated device in said means whereby when the level of the liquid in said ladle is lowered said ladle will be raised a substantially corresponding amount.

4. In combination with a crane hook and a liquid carrying ladle, means for suspend-

ing said ladle from said hook comprising a spring actuated equalizing device whereby 65 when the level of said liquid in said ladle is lowered said device will be shortened to lift said ladle a corresponding amount.

5. In combination, a liquid carrying ladle suspended from a crane hook by an automatically contractable connection, said connection being such that any drop of the level of said liquid in said ladle is automatically compensated for by a corresponding contraction of said connection and subsequent 75 rise of said ladle.

6. In combination, a liquid carrying ladle suspended from a crane hook by an automatically extensible and contractable connection, said connection being such that the 80 relative distance between the surface of the liquid in said ladle and said hook remains substantially constant regardless of the amount of liquid in said ladle.

7. In combination, a crane hook and a 85 liquid carrying ladle suspended therefrom by means of a spring controlled extensible and contractable connection, said connection being such that any change in the weight of the liquid in said ladle due to a change 90 in the amount of liquid therein is accompanied by a corresponding change in the length of said connection whereby the level of said liquid in respect to said hook automatically remains substantially constant. 95

8. In combination with a crane hook and liquid carrying ladle suspended therefrom by a spring controlled automatically extensible and contractable connection, the rate of deflection of said spring being such that 100 for each increment of drop in the level of the liquid in said ladle a corresponding increment of contraction of said connection will occur.

9. The combination with a crane hook and a liquid carrying pouring ladle, of means for suspending said ladle from said hook comprising an automatically extensible and contractable spring balanced device the length of which varies in direct proportion to the 110 weight of the liquid in the ladle and in amount corresponding with the depth of the liquid in said ladle.

10. The combination with a crane hook and a liquid carrying pouring ladle, of means for suspending said ladle from said hook comprising a spring balanced device automatically contractable as said liquid is poured from said ladle an amount sufficient to keep the pouring lip of said ladle in the 115 operation of pouring at a substantially constant distance from said hook.

Signed by me at South Bend, Indiana, U. S. A., this 22nd day of April, 1925.

WILLIAM C. RENGERT.
